Harry Radinsky

UNITED STATES PATENT OFFICE

HARRY ESTEROW, OF NEW YORK, N. Y.

CIGAR LIGHTER

Application filed January 31, 1930. Serial No. 424,832.

This invention relates to an improvement in the type of cigar lighter disclosed in my Patent No. 1,737,964 dated December 3, 1929. In the type of lighter there disclosed, I combine a watch with a lighter. The watch is wholly carried and supported by a hinged door which overlies one of the faces of the fuel chamber of the lighter. This present invention relates to a means for assembling 5 the various elements which make up the watch-holding means.

The primary object of this invention is to provide a simple, sturdy and effective means for attaching a watch to a door, plate or other 15 similar part of a cigar lighter without the use of solder or other similar expensive assembly means. I secure this result through a utilization of parts to be fully described hereafter and more particularly pointed out 20 in the claims appended hereto.

Reference is to be had to the accompanying drawings, forming a part hereof in which

Figure 1 is a front elevation of a cigar lighter made in accordance with my invention; 25

Figure 2 is a perspective view of the watch crystal-supporting bezel before the same is placed in position on the door of the lighter;

Figure 3 is a transverse sectional view of 30 the door showing how the watch movement case is held thereon;

Figure 4 is a view of the rear face of the door disclosing the means for engaging and holding the watch movement case; and

Figure 5 is a view partly in section of the 35 several parts, which united comprise the watch supporting means.

Throughout the various views of the drawings, similar reference characters designate 40 similar parts.

In the embodiment of my invention disclosed in the accompanying drawings, 1 indicates the body or fuel chamber of a cigar 45 lighter. The same is usually tubular in form and has its opposite ends closed by plates 2 and 3. The lower plate 3 is provided with a filling opening that is normally closed by a threaded plug 4. The upper plate 2 supports on its top face the lighter operating

mechanism of conventional form, consisting of a flint tube 5, thumb wheel 6, adjusting screw 8 and a wick guard 7 that is pivotally mounted on a standard 9.

As these operating parts form no particular part of the present invention, it is unnecessary to give further details of the same.

At 10 is shown a door secured over one face of the fuel chamber 1. This door is preferably movable and to permit such movement, it may be hinged at its side edge 11 by invisible hinges not shown. This door may, of course, be movably secured in any other way to the fuel chamber 1. The fuel chamber 1 is usually provided in articles of this character with a depression in one of its side walls, into which a watch movement projecting from the back face of the door 10 may protrude when the door is in its closed position.

Since the structure thus far described is fully shown in my Patent No. 1,737,964, further details of the same are deemed unnecessary.

The door 10 is provided with an aperture 75 12 and this aperture receives a bezel 13. The bezel 13 is of a shape to snugly fit within the aperture 12. Said bezel is provided with a surrounding flange 14 which, when the bezel is fitted within the aperture 12, lies against 80 the front face of the door 10 and surrounds the aperture 12. The bezel is also provided with tongues 15, one of these tongues being provided on each of the four sides of the bezel. Thus, when the bezel is fitted in the 85 aperture 12, the tongues protrude through said aperture and extend beyond the back face of the door 10.

At 18 is disclosed a cup-like frame which is provided with a peripheral enclosing wall or flange 19 and an inturned or inwardly projecting flange 20. The member 18 is thus provided with an aperture 21 corresponding in size, or slightly larger than the aperture 12 in the door 10. The member 18 is placed flat against the back face of the door 10 with its opening 21 in registration with the aperture 12 in said door. Thereupon, the tongues 15 are bent over the flange 20 on the member 18 as clearly disclosed in Figure 4, 100

so that as a result, the door 10, bezel 13 and member 18 are securely united.

The bezel 13 is provided with corner flanges 16 which project inwardly and are located between the tongues 15 and the outer flange 14, these flanges 16 acting as a seat for a watch crystal 17 which is frictionally held by the bezel against said seat.

From the description thus far given, it will be seen that the plate-like door 10 is provided with a crystal-holding bezel and that said bezel, through the medium of its bent-over tongues 15, securely holds a cup-like retaining member 18 on the back of the door.

The watch movement case is disclosed at 22 and the same consists of a pair of telescoped members 23 and 24 which snugly fit together and are frictionally held in such relationship. This case 22 holds a watch movement of conventional form, which is not shown, the member 24 of such case being provided with a front opening 35, through which the dial of the watch movement is visible. The case 22 with a contained watch movement fits within the cup-like frame 18 and is held in snap engagement therewith by means of inter-engaging projections 25 and 26 provided on the parts 22 and 18 respectively.

The flange 19 of the member 18 is preferably provided with a recess 36 through which a winding stem on the watch movement may protrude. This winding stem is provided with the usual head 29 that is exposed through an opening 28 provided in the door 10.

From the foregoing, the simplicity and ease of assembly of my improved structure will be apparent. The bezel 13 and member 18 are securely held in position with respect to the door 10 by means of the bent-over flanges 15. The watch movement casing 22 may be readily snapped in and out of the member 18 for instant removal or inspection of the watch movement. The various openings 12, 19 and 35 in the parts 10, 18 and 22 permit the dial of the watch to be visible through the watch crystal 17 at all times.

Thus, through the construction described, I provide a sturdy, permanent structure which may be inexpensively assembled.

Having described my invention, what I claim is:

1. In a cigar lighter, a plate having an opening, a crystal-receiving bezel adapted to fit therein, said bezel having tongues extending through the opening in the plate and bent over at the back of the plate to secure the bezel in position, and means maintained on the back of the plate by said tongues for engaging and holding a watch-movement case.

2. In a cigar lighter, a door, said door having an opening, a crystal-receiving bezel adapted to fit therein, said bezel having an outer flange adapted to rest against the outer face of the door around the opening therein, said bezel also having tongues bent over at the back of the door to secure the bezel in position, and means maintained on the back of the plate by said tongues for so engaging and holding a watch movement case that said case is maintained and wholly supported by said door.

3. In a cigar lighter, a plate having an opening, a bezel having tongues bent over at the back of the plate for maintaining said bezel in the opening, a frame engaged at the back of the plate by said tongues and held against said plate, and a watch movement case detachably held by said frame.

4. In a cigar lighter, a plate having an opening, a crystal-receiving bezel adapted to fit therein, a frame having an inturned flange held against the back of the plate, tongues on the bezel extending through the opening in the plate and bent outwardly and over the inturned flange on the frame for maintaining said frame and bezel in position on the plate.

5. In a cigar lighter, an apertured cover mounted on the lighter and adapted to carry a watch movement, a case for said movement, means fixed to the back of the cover for detachably engaging with the watch movement case, said means comprising a flanged frame and a bezel on the front of the cover, said bezel having tongues extending through the aperture in the cover and bent over the flange on the frame.

Signed at the city, county and State of New York, this 29 day of January, 1930.

HARRY ESTEROW.
